CONTAINER AND APPLICATOR FOR
COSMETICS

M. Martin Gordon, Chicago, Ill.

Application October 31, 1938, Serial No. 237,855

5 Claims. (Cl. 91—67.2)

While this invention may be adapted for various uses it is particularly applicable for use in connection with applying a liquid cosmetic or rouge for coloring the lips. While various applicators have heretofore been proposed for applying cosmetics generally, none of them are adapted for the particular purposes for which the present device is intended. Some of such applicators are not adapted for holding a sufficient amount of liquid for easy application and others are so constructed that any excess of liquid or coloring will tend to run down the applicator and onto the fingers of the user, or in other ways are not satisfactory for the present purposes.

The objects of the present invention are to provide an improved receptacle for holding liquid cosmetics with means permanently associated therewith for applying the cosmetic; to provide an applicator for liquids having an elongated absorbent member, a portion of which is adapted to carry a supply of the liquid and another portion being adapted to absorb any excess as the liquid is being applied; to provide an applicator comprising a bottle cap having a novel form of vehicle for receiving and applying a liquid cosmetic; and to provide such other novel features and advantages as will appear more fully from the following description.

In the accompanying drawing illustrating this invention,

Fig. 1 is a side view of my improved device;

Fig. 2 is a longitudinal sectional view;

Fig. 3 is an enlarged detail of the applicator; and

Figs. 4, 5 and 6 are details of the swab portion or absorbent vehicle for applying the liquid.

While my improved container may be made in any desired size it is shown in the drawing on a somewhat enlarged scale for convenience in illustration. It comprises a container or bottle 7 of any suitable material having a threaded neck for receiving a screw cap 8. The cap has a downwardly and inwardly extending hollow projection 9 for receiving and supporting the swab or applicator member proper 10. This member is of the particular construction shown and is made from a twisted wire 11 having brush-like or absorbent material such as cotton or other absorbent fibres

12 interwoven with the strands and supported thereby. The wire 11 is formed of suitable material, as for instance Monel metal, which will resist or not be affected by the liquid rouge or other material which is to be used. This composite rod as shown in Fig. 4 is doubled or bent

to provide a rounded end 13 and the branches are brought close together as shown in Figures 5 and 6 so that it has the appearance of a single stick or rod of absorbent material. The ends are preferably bent back for a short distance as shown at 14 to provide a substantial fastening portion for securing the same to the cap. This end is inserted in the hollow projection 9 as shown particularly in Figure 3 and fits closely therein but is further held in position by any suitable cement or adhesive. This fastening is particularly effective as the adhesive adheres to the absorbent material of the applicator 12 and unites the same securely to the inner walls of the projection.

When the applicator is in normal position in the liquid and not in use, the lower end of the swab portion 10 will extend down into the liquid as shown in Figure 1 and the upper end of the swab portion will extend above the liquid and will ordinarily be drier or less saturated than the lower portion. When the applicator is detached from the bottle and the saturated lower end applied to the lips, any excess liquid which would otherwise tend to run down the stem portion of the applicator will be absorbed or caught by the upper or less saturated portion of the swab and thereby prevents its running down into the cap or onto the fingers of the user.

When the applicator is to be used, the twisted wire rod provides flexible springiness combined with enough rigidity so that this applicator can be passed over the varied contours of the lips, yielding sufficiently to allow thorough and yet light, comfortable contact with all the surfaces of the lips which it is desired to color.

Between the two parallel elements of this rod grooves or troughs are formed, which retain a portion of the liquid, assisting in distributing it evenly in whatever position the applicator may be held. This is an unique feature and important for the reason that lip color applicators must frequently be held in a position with what is here described as the "lower portion" extending upwardly. Thus when the applicator is up-ended, its particular construction retains enough of the liquid on and near the rounded extremity so that convenient and complete application may be made without redipping or replenishing.

The effect of twisting the fibre about the spirally-twisted wire gives a "toothed" or brushlike outward thrust termination or projection to the fibres, resulting in a more softly blended application of the color, especially at the edges of the lips. From this description it will be seen that I

provide a particularly convenient and effective means for carrying and applying liquid rouge, "liquid lipstick", or the like, and while I have shown a preferred form of the invention as manufactured and used, it will be apparent that modifications may be made without departing from the scope thereof as set forth in the following claims, in which I claim:

- 5 1. A container and applicator for cosmetics, comprising a bottle, a closure for the bottle having an inwardly extending hollow projection, an applicator member made of a section of twisted wire with absorbent material bound therein bent back upon itself to provide a rounded extremity and having the ends also bent back upon the adjacent portions to form a holding portion, said holding portion fitting in the hollow projection and held therein by an adhesive.
- 10 2. The combination with a bottle having a threaded neck, of a threaded cap engaging with the neck and having a hollow downwardly extending projection, an applicator member comprising a twisted wire formed of metal which will be resistant to the liquid with which the applicator is to be used, said wire having absorbent material incorporated therewith, the wire being bent at the middle with the branches arranged parallel and adjacent to each other, the ends of the wire being fastened in the hollow projection.
- 15
- 20
- 25

3. An applicator for the purposes set forth, comprising a closure for a receptacle, a carrier vehicle for applying liquid, consisting of a wire having absorbent fibres secured thereto substantially the full length thereof, the wire being bent back upon itself to provide a generally rounded extremity which is adapted to project down into the liquid to be applied and the free ends of the wire being secured to the closure.

4. A container and applicator for cosmetics, comprising a bottle, a closure for the bottle having a preformed hollow portion, an applicator member made of a section of twisted wire with absorbent material bound therein bent back upon itself to provide a rounded extremity and having at least one end also bent back upon an adjacent portion to form a holding portion, the free ends of said applicator member fitting into and being rigidly secured within said hollow portion.

5. An applicator member for cosmetic preparations comprising handle means, a twisted wire rod having absorbent material extending substantially the full length thereof, said rod being bent back upon itself to provide a generally rounded extremity, and the two free ends of said rod being secured in an opening in said handle means.

M. MARTIN GORDON.
